United States Patent

Des. 239,999
Patented May 25, 1976

239,999

DISH

Hubert E. Christian, Phoenix, Ariz., assignor to Dart
Industries Inc., Los Angeles, Calif.

Filed Dec. 27, 1974, Ser. No. 537,012

Term of patent 14 years

Int. Cl. D7—01

U.S. Cl. D7—23

FIG. 1

FIG. 2

FIG. 3

FIG. 4

FIG. 5

FIG. 1 is a perspective view of a dish showing my new design;

FIG. 2 is a side elevation view;

FIG. 3 is a top plan view;

FIG. 4 is a bottom plan view; and

FIG. 5 is a cross-sectional view on an enlarged scale taken along line 5—5 of FIG. 3.

I claim:

The ornamental design for a dish, substantially as shown and described.
